(57) CLAIM

The ornamental design for a ball-point pen, as shown and described.

DESCRIPTION

FIG. 1 is a perspective view of a ball-point pen showing my new design;

FIG. 2 is a front elevational view;

FIG. 3 is a rear elevational view;

FIG. 4 is a right side elevational view (the left side elevational view is a mirror image of the right side view);

FIG. 5 is a top plan view;

FIG. 6 is a bottom plan view;

FIG. 7 is an enlarged cross-sectional view of the grip taken in the direction 7—7 in FIG. 2;

FIG. 8 is an enlarged cross-sectional view of the barrel taken in the direction 8—8 in FIG. 2; and,

FIG. 9 is a perspective view with the writing tip shown extended.
